UNITED STATES PATENT OFFICE.

WILLIAM R. SEIGLE, OF NASHUA, NEW HAMPSHIRE.

MACHINE FOR WINDING PULP TUBES.

1,037,671.

Specification of Letters Patent. Patented Sept. 3, 1912.

Application filed December 29, 1911. Serial No. 668,417.

To all whom it may concern:

Be it known that I, WILLIAM R. SEIGLE, a citizen of the United States, and resident of Nashua, in the county of Hillsboro and State of New Hampshire, have invented new and useful Improvements in Machines for Winding Pulp Tubes, of which the following is a specification.

My invention relates to machines for winding pulp tubes, and consists particularly in devices for equalizing the density of such tubes so that when completed the tube shall be homogeneous throughout its entire length.

Machines of the general character to which my present improvement may be applied are shown and described in detail in applications for Letters Patent of the United States filed by me and copending herewith, to wit, Serial Nos. 630,921, and 630,922 filed June 2, 1911. Those machines are characterized by the coöperative functional relationship of a carrier to convey a thin web of moist pulp, winding mandrels mounted in a revoluble mandrel frame, so that one mandrel at a time bears upon and winds the thin web of pulp spirally in superposed layers upon itself, taking the web from the web carrier, and provisions for bringing the weight of the mandrel frame and mandrels to bear on the web carrier at the line of contact between the carrier and the mandrel which is actively engaged in winding a tube.

By virtue of sundry improvements which need not be described here, since they form no part of the present invention, for which Letters Patent are sought, it has become industrially feasible to wind pulp tubes under greater pressure than heretofore, so that the resulting product has high density and is therefore adapted to a larger number of uses than the pulp tubes of rather loose consistency produced by machines earlier employed in this art. The utilization of heavier pressures has, however, developed further and other difficulties and defects in the tubular products, for the reason that the winding mandrels even though made of stiff metal sometimes spring during the winding operation, so that the density of the tube along its middle is less than at the ends. This difference might not be a serious matter in many situations but when, as is often the case, tubes of this character are impregnated with insulating material

such as asphalt, and then hardened, for use as insulating envelopes for electric wires, insulation tests disclose a greater susceptibility to penetration in the middle of the tubes than at the ends, the insulating capacity of the tube walls sometimes falling below the prescribed resistivity.

In order to conserve the advantages due to tube winding under high pressure and also to correct the defects above indicated, I have invented the improvements hereinbelow to be described which are illustrated in the accompanying drawings, in which—

Figure 1 is a front elevation of portions of a tube winding machine of the character indicated; and Fig. 2 is a section on an enlarged scale through the middle of the mandrel frame taken transversely to Fig. 1 and viewed as from the left of that figure.

Among portions of a tube winding machine of the character designated illustrated in the drawings, are the end standards, A, A', the sectional suction roll R, the web carrier of felt or similar material C, the mandrel frame comprising heads, H, H', and mounted on the shaft H², the mandrels M journaled in the mandrel heads, the driving gear generally designated by G and the detent mechanism generally designated by D in Fig. 2.

The mandrels M are four in number in the illustration shown and are mounted in the mandrel heads in such manner that when a tube has been wound upon a mandrel it may be removed from the mandrel frame and another substituted. In Fig. 1 only the upper and lower mandrels are shown, the middle one on the side toward the observer having been removed and the middle one on the rear side being obscured from view by the other parts of the machine shown in the drawing. So far the portions of the machine mentioned are substantially the same as those which appear in the machines described in my copending applications aforesaid and these are indicated merely to designate the general character of machine to which my present improvements are applied.

In addition to the foregoing parts, the mandrel frame is provided with four radially disposed slots, h in the head H, and h' in the head H'. Each of these slots is located adjacent to a mandrel M and serves as a sliding bearing for the trunnions of a presser roll P of which four are shown corresponding to the four mandrels. These

presser rolls are made stiff and heavy, preferably of iron or steel, and their surfaces should be roughened or clothed with wire gauze as indicated in the figures, so as not to 5 couch the pulp off from the mandrel.

When one of the mandrels M is brought into operative conjunction with the web carrier C, the presser roll P automatically descends and bears upon the upper limb of 10 the mandrel M and turns by contact with the mandrel, not only by its weight correcting any tendency of the mandrel M to spring at the center, but also assisting in the work of compressing and compacting the pulp 15 tube as it is wound on the mandrel. When the desired thickness of tube has been built up on the mandrel, the mandrel frame is rotated a quarter turn, either by hand or 20 preferably automatically, so that the mandrel and wound tube is eventually presented at the front of the machine to be removed in any known manner. The automatic mode of thus shifting the mandrel frame is indicated in the figures where D (Fig. 1) represents 25 comprehensively a detent mechanism, a part of which is the detent 'D' which engages with the notches N in succession as the mandrel frame is intermittently rotated. At intervals which are predetermined by the 30 growth of the pulp tube upon the mandrel M, which causes the entire mandrel frame to rise in the bearings provided in the standards, A, A', the detent D' is abruptly withdrawn from the notch N' and the driving 35 gear G (Fig. 1), which constantly operates frictionally upon the shaft H' throws the mandrel frame backward toward the rear of the machine, (the rotation being right handed as viewed in Fig. 2); until the detent D' 40 stops the mandrel frame by engagement with the next notch N. The operation of this mandrel frame shifting mechanism is

described in detail in my said co-pending application, Serial No. 630,922.

In the arrangement herein shown, those presser rolls which are idle are supported by the slots, h, h', two of which are in horizontal position, the upper presser roll resting at the lower ends of the vertical upper slots h'. When in the shifting movement of the 50 mandrel frame, a mandrel descends to the carrier C, it receives the weight of its presser roll which slides or rolls automatically into position. When, however, the mandrel M is to be moved for purposes of removing the 55 pulp tube, its presser roll does not bear upon it but rests idly in the holding slots h, h'. The size and weight of the presser rolls P will obviously be varied to suit different sizes of pulp tubes and mandrels M and may 60 vary also with the degree of pressure selected for tube winding.

I claim:

1. In a tube winding machine of the character described, the combination of a rotary mandrel frame, mandrels in bearings on said frame, and presser rolls mounted in the frame to bear on the mandrels as they take position for tube winding. 65
2. In a tube winding machine of the character described, the combination of a rotary mandrel frame, mandrels in bearings on said frame, the frame provided with radially disposed slot bearings for presser rolls, presser rolls with trunnions working 70 in said slots, to bear on the mandrels as they take position for tube winding. 75

Signed by me at Boston, Massachusetts, this twenty third day of December 1911.

WILLIAM R. SEIGLE.
